BLADE SHARPENER AND METHOD OF
MAKING THE SAMELouis J. Raab, Lower Saucon Township,
Northampton County, Pa.

Application May 13, 1950, Serial No. 161,756

6 Claims. (Cl. 51—198)

1

The present invention relates to devices to be used in the sharpening of cutting blades, particularly razor blades, and to methods of making such devices.

Numerous types of razor blade sharpening devices have heretofore been suggested, made and used and in many of these the actual sharpening element, that is the element over which the blade to be sharpened is repeatedly passed, has been fabricated of leather or other cured animal hide, which has been given increased pliability by the use of liquid treatment agents, and sometimes given increased capacity to wear away the metal of the knife being sharpened by the addition of granular or powdered abrasive substances. It has also been heretofore suggested that a single sharpening operation performed on a cutting blade, for instance a razor blade, might with advantage be performed in two steps, the blade being first passed over a surface the characteristics of which are such that a relatively rapid wearing away of the metal of the blade is effected, and then over a surface having less capacity to wear away the blade and increased capacity to impart a smooth continuous edge, the metal thus being subjected to successive operations which may be called roughing and finishing operations. Commonly the two surfaces of such a sharpening device are designated starting and finishing surfaces, and the present invention relates to such a device having one sharpening surface for starting the operation and a second for finishing the sharpening operation and which leaves the sharpened blade with a very superior cutting edge.

Essentially the improved blade sharpener comprises two strips of cured hide suitably secured upon the opposite faces of a rigid base or supporting member equipped with a handle. While the supporting member is rigid in an overall sense it is so formed that each of the sharpening strips is slightly yieldable under pressure, a characteristic found to be highly desirable in devices of this character. The starting element of the sharpener preferably comprises a strip of pigskin throughout which are distributed minute pockets of an abrasive mixture, for instance a mixture of aluminum oxide, silicon carbide and zinc oxide. The abrasive material is caused to penetrate the pigskin quite deeply, generally substantially all of the way through the outer porous surface of the pigskin strip, a novel method for effecting such deep penetration comprising an important feature of the invention.

In order to effect such deep penetration a measured quantity of the intermingled powdery

abrasives is mixed with a quantity of petroleum jelly or like substance, which has been reduced by heat to a liquid form, and this mixture is spread, as by means of a brush, over the surface of the pigskin strip which is to serve as a holder or matrix therefor. The strip with its coating of mixed petroleum jelly and abrasive powder is then subjected to a heating operation, heat of sufficient degree being applied for the length of time found to be necessary, to cause the liquefied petroleum jelly and the powdered abrasive carried thereby to penetrate deeply into the pigskin, passing between the bundles of fibers of which the pigskin is composed and the abrasive material being deposited in this manner in the spaces between the fibers. The application of heat not only serves to maintain the jelly in such liquid condition that it may penetrate the pigskin to the maximum extent but further facilitates such penetration by causing the fibers of the pigskin to shrink and the spaces between the fibers to increase. The resulting article is a sharpener of the "starter" type, well able to serve as a means for rapidly sharpening a tool blade of any character.

The finishing strip of the sharpener is fabricated in a generally similar manner but the cured hide utilized is cowhide or horsehide and the abrasive materials incorporated into the hide by using petroleum jelly and heat are different in composition, the abrasive powder being a mixture of ferric oxide, zinc oxide and aluminum oxide. The cow or horse hide strip, coated with a mixture of petroleum jelly and the powdered oxides, is heated as before, the purpose likewise being to enlarge the interstices between the fibers of the hide and maintain the petroleum jelly in liquid form, thus facilitating deep penetration of the abrasive oxides.

One of the completed sharpeners, in a preferred form, is illustrated in the accompanying drawing, in which

Figure 1 is a perspective view of the sharpener;
Figure 2 is a side elevation partly broken away;
and
Figure 3 is a section on line 3—3 of Figure 2.
The sharpener shown is in the form of a paddle, having a body 10 with a suitable handle 11, the starting and finishing strips being secured by suitable adhesives to the parallel opposite faces of body 10, one of these strips, which is indicated at 12, being the starting strip and the second strip, indicated at 13, being the finishing strip. It will be observed that the body 10 is not solid but that it is provided with two slots

14 and 15 respectively, these slots being parallel to each other and parallel to the strips 12 and 13 respectively. By reason of the provision of the slots 14 and 15 the major portions of the two strips 12 and 13 are yieldably supported, the wooden tongue 16 intermediate slot 14 and strip 12 yielding to pressure applied to the surface of strip 12 in the ordinary stropping operation, and the strip 13 being likewise yieldably supported by the yieldable tongue 17, intermediate slot 15 and that strip. Spacing blocks 18 and 19 are inserted into the slots 14 and 15, at the open ends of these slots, to prevent excessive deflection of the tongues 16 and 17 and to normally maintain the slots uniform in width. The walls of the slots are transversely serrated as indicated in Figures 2 and 3, it having been found that a serrated surface such as that shown upon the underside of tongue 16 for instance gives that tongue increased yieldability, for a given tongue thickness, a desirable thickness being approximately one-eighth inch.

In processing the starter strip 12, which is of cured pigskin, a mixture of powdered abrasive of novel character is first made. Aluminum oxide, silicon carbide and zinc oxide are ground to such fineness that each will pass through a 325 mesh screen, or a screen of approximately that mesh. The three oxide powders thus obtained are thoroughly intermingled, the resulting powder comprising, by volume, 65% aluminum oxide, 25% silicon carbide, and 10% zinc oxide, a mixture which has been found to be particularly effective in actual use. A quantity of these intermingled oxides is then mixed with petroleum jelly which has been preferably heated to approximately 190° F., one part of the intermingled oxide, by weight, being added to two parts, by weight, of petroleum jelly, although the ratio of powdered oxide to jelly may be varied considerably if desired.

The mixture of powdered oxide and petroleum jelly, which is heated and in fluid condition, is then applied to the surface of the pigskin strip by any suitable means, as for instance by brush. A fairly thick coating is desirable, a standard teaspoon full of the mixture being applied, for instance, to the surface of a pigskin strip measuring 8 3/4 inches in length and 1 3/4 inches in width, the coating being spread evenly or uniformly over the surface.

After the strip has been coated heat is applied to both the strip and the coating on its surface, this strip being maintained in horizontal position during the coating operation. Heats of various intensities may be employed and for various periods of time, the objective being to shrink the fibers of the pigskin without, however, damaging the strip in any way and to maintain the carrier, i. e. the petroleum jelly, in the form of a thin liquid to facilitate its entry into the pores or inter-fiber spaces of the pigskin strip, taking with it the powdered oxides with which it has been mixed. It has been found that the heating operation may be adequately accomplished by placing the coated surface of the strip approximately two inches distance from a heating element which develops a constant temperature in the neighborhood of 1300 to 1400° F., the strip being maintained in proximity to the heat (although preferably oscillated in its plane) for some three to five minutes. A pigskin strip thus treated will be found upon examination to have been very deeply penetrated by the petroleum jelly and the powdered oxides carried by the

75 jelly and to constitute in actual use a sharpening element of superior character.

The finishing strip may be, as previously stated, fabricated in substantially the same way as the starting strip, a mixture of abrasives being first prepared, a quantity of such abrasives, by weight, being added to twice that much, by weight, petroleum jelly which is heated to 190° F., the mixture spread upon the surface of the leather strip, and the strip and coating being subjected to heat as before. Instead of pigskin, however, the finishing strip is of horsehide or cowhide, these materials being different in texture from the pigskin and being more suitable to finishing operations in the sharpening process. Furthermore, the abrasives which are added to the petroleum jelly have different characteristics, comprising intermingled oxide of iron, zinc and aluminum oxide powdered so as to pass a screen of approximately 325 mesh. Thus such a quantity of intermingled abrasives may comprise, by volume, 55% ferric oxide, 5% zinc oxide, and 40% aluminum oxide.

The 40% aluminum oxide is in the nature of a sediment which remains after treatment of aluminum oxide with water, such sediment being obtained in the following manner. Eight fluid ounces of aluminum oxide are first ground to such fineness that they will pass through a screen of approximately 325 mesh. The powdered oxide is then placed in two quarts of water and the container containing the water and powder is then shaken vigorously for a minute or two. Substantially all of the water is then siphoned out of the container and the container and the small amount of water, with the powder which has largely settled to the bottom, is allowed to stand for twenty-four hours. Heat is applied then to completely evaporate the water and the sediment which remains at the bottom, and which is a sediment of aluminum oxide, is suitable for use in forming the abrasive mixture which is to be added to the petroleum jelly.

After the mixture of abrasive powder and jelly has been formed it is applied as before, subjected to heat as in the case of the starting strip, and the resulting "finishing" strip will be found to be especially well adapted to impart to a razor or knife blade a highly polished, extremely keen and smooth and continuous edge.

Having thus described the invention, what is claimed as new and desired to be secured by Letters Patent is:

1. In a blade sharpener, a strip of cured animal hide having an imperforate stropping surface the pores or inter-fiber spaces of which, underlying said surface, contain deposits of a mixture of powdered abrasive comprising aluminum oxide, silicon carbide, and zinc oxide, more than half of such mixture, by weight, being powdered aluminum oxide.

2. In a blade sharpener, a strip of cured animal hide having an imperforate stropping surface the pores or inter-fiber spaces of which, underlying said surface, contain deposits of a mixture of powdered abrasive comprising aluminum oxide, silicon carbide, and zinc oxide, approximately 65%, by volume, of said mixture being aluminum oxide, approximately 25% silicon carbide and approximately 10% zinc oxide.

3. The method of introducing finely powdered abrasive material into the pores or inter-fiber spaces of a strip of cured animal hide which comprises, mixing such material with petroleum jelly, spreading a layer of such mixture upon the

surface of the strip, and subjecting the strip and the mixture thus applied to the action of heat until the jelly and abrasive carried thereby has penetrated the hide.

4. The method of introducing finely powdered abrasive material into the pores or inter-fiber spaces of a strip of cured animal hide which comprises mixing one part, by weight, of powdered abrasive with two parts, by weight, of petroleum jelly which has been liquefied by heat, 10 spreading a layer of the mixture thus formed on the surface of the strip, and heating the mixture covered strip until the mixture has penetrated the same.

5. The method set forth in claim 4 in which 15 the petroleum jelly is heated to a temperature of approximately 190° F. before the powdered abrasive is mixed therewith.

6. The method set forth in claim 4 in which the coated strip is subjected to radiant heat to 20 cause the fibers to shrink and to maintain the jelly in substantially liquid form during penetration.
